CASING FOR A STENOGRAPHIC MACHINE

John Kreidich, Arlington Heights, Ill., assignor to The
Hedman Company, Chicago, Ill., a corporation of
Delaware

Filed Jan. 9, 1968, Ser. No. 10,102

Term of patent 14 years

(Cl. D64—11)

FIG. 3.

FIG. 4.

FIG. 5.

FIG. 1 is a perspective view of a casing for a stenographic machine showing my new design;

FIG. 2 is a plan view thereof;

FIG. 3 is a left side elevational view thereof as it appears without the broken line illustration of the keys and shift and spacer bar;

FIG. 4 is a front elevational view thereof as it appears without the broken line illustration of the keys and shift and spacer bar; and

FIG. 5 is a rear elevational view thereof.

The appearance of the right side is substantially a mirror image of the left side. The broken line showing of the keys and the shift and spacer bar in FIGS. 1 and 2 is merely for illustrative purposes.

I claim:

The ornamental design for a casing for a stenographic machine, substantially as shown and described.
